United States Patent Office

Des. 231,285

Patented Apr. 16, 1974

231,285

CRIB END

Robert V. Jacobs and Allen D. Jacobs, Los Angeles, Calif., assignors to Questor Corporation, Toledo, Ohio

Filed June 22, 1972, Ser. No. 279,221

Term of patent 14 years

Int. Cl. D6—01

U.S. Cl. D6—14

Fig. 1.

Fig. 2.

Fig. 3.

FIG. 1 is a front elevational view of a crib end showing our new design;

FIG. 2 is a side elevational view; and

FIG. 3 is a top plan view.

The opposite side of the panel shown in FIG. 1 of the disclosure is plain and unornamented.

We claim:

The ornamental design for a crib end, as shown and described.
